UNITED STATES PATENT OFFICE.

EMANUEL CLEMENS, OF EAST ORANGE, NEW JERSEY, ASSIGNOR TO SUPERIOR IVORY
BUTTON COMPANY, OF NEWARK, NEW JERSEY, A CORPORATION OF NEW JERSEY.

BUTTON-MAKING MACHINE.

Application filed April 3, 1919. Serial No. 237,121.

To all whom it may concern:

Be it known that I, EMANUEL CLEMENS, a citizen of the Dominion of Canada, but having declared my intention to become a citizen of the United States, and now residing in the city of East Orange, county of Essex, and State of New Jersey, have invented a new and useful Improvement in Button-Making Machines, of which the following is a specification.

While my invention is more specifically adapted to the manufacture of buttons from the well-known vegetable ivory nut, or as known in commerce, the corozzo nut, yet by slight changes in the holding devices, it may be utilized in the manufacture of buttons from any material, such as mother-of-pearl, ivory, bone, wood, metal, etc.

While button making machines are well known in the art, yet my improvement contemplates many changes, looking to the increased output, making the machines as nearly automatic as conditions will permit, improving the quality of the product, making it possible to utilize a larger proportion of the raw stock with fewer "culls" or discards; and in general, to improve and simplify the mechanical structure of button making machines.

In carrying out my invention, I make use of the mechanism and structures substantially as described in the following specification and illustrated in the accompanying drawings, wherein:

Fig. 1 is a front elevation;
Fig. 2 is a right end elevation;
Fig. 3 is a rear elevation;
Fig. 4 is a left end elevation of the complete machine.
Fig. 5 is an enlarged plan.
Fig. 6 is an elevation of a portion of the rear side of the machine.
Fig. 7 is an elevation of the main drive shaft and the parts immediately connected therewith and driven thereby.

Fig. 8 is a detail of the intermittent driving mechanism.
Fig. 9 is a plan of the main drive shaft and its supporting bracket.

Fig. 10 is a detached side elevation of the main driven cam shaft.
Figs. 11, 12, 13, 14, 15 and 16 are respectively elevations of the several cams mounted upon the cam shaft.

Fig. 17 is a detached elevation of the short cross shaft, which is driven by the cam shaft.

Fig. 18 is an elevation of two of the cams mounted upon the short cross shaft.

Fig. 19 is a detached view of the independent severing mechanism and the brake for the chuck plate.

Fig. 19' is a plan view of the bell-crank actuating lever.

Figs. 20, 21 and 22 are respectively plan, end and sectional views of the severing tool.

Fig. 23 is a detached elevation of the chuck plate brake.

Fig. 24 is a detached elevation of the chuck releasing mechanism and the "spotter" camplate releasing mechanism.

Fig. 25 is a detached elevation partly in section of the cam for operating the releasing mechanisms.

Fig. 26 is a similar view illustrating the treadle operated mechanism for operating the releasing mechanisms.

Fig. 27 is a longitudinal section of the spotter mechanism.

Fig. 28 is a cross section through the gear case of the spotter mechanism.

Fig. 29 is a gear plan of the spotter gear train and ratchet.

Figs. 30, 31, 32 and 33 are respectively rear, plan, front and sectional views of the chuck plate.

Fig. 34 is a diagrammatic view of the chuck plate, showing the successive positions of the seven chucks during a complete cycle of operation upon the buttons.

Fig. 35 is a fragmentary view of the chuck plate, showing the relative positions of the spotter actuating mechanism and the chuck plate brake; also the position of the auxiliary chuck holding shoe for preventing the shifting of the button stock.

Fig. 36 is a broken sectional view of the tool actuating bars.

Fig. 37 is a sectional view of the mechanism for effecting a longitudinal adjustment of the cutting tools by hand.

Fig. 38 is a sectional view of the main drive shaft.

Fig. 39 is a view of the guide bracket for holding the tool actuating bars against rotation.

Fig. 40 is a detached view of the automatic tool adjusting mechanism.

Figs. 41 and 42 are respectively detached views of the mechanism for reciprocating the tool actuating bars.

Fig. 43 is a detached view of the mechanism for actuating the chuck holding shoe.

Figs. 44 and 45 are respectively side and end views of the mechanism for actuating the spotter.

Fig. 46 is a view of the mechanism for operating the chuck plate locking device.

Fig. 47 is a sectional view of a piece of button stock showing the location of the button cut therefrom.

Fig. 48 is a similar view showing another piece of button stock of different shape showing the location of the button cut therefrom.

The main frame 1 of the machine is generally rectangular, as shown in plan in Fig. 5. At one end is the bracket 2, having the bearings 3, in which the main driving shaft 4 is mounted. Power is communicated to the shaft 4 from the driven counter pulley 5, through the belt 6, which passes over the direction pulleys 7, to the pulley 8 upon the shaft 4. Upon the opposite end of shaft 4 is a worm 9, which engages and drives the worm wheel 10, the latter being mounted upon the shaft 11 which is carried in bearings 12 and 13 on the front of the frame 1. Upon the shaft 11 there are several cams mounted, which will be referred to hereafter in connection with the elements which they operate.

Upon the shaft 11, there is mounted adjacent to the worm wheel 10, a single-tooth disk element of the well-known Geneva stop as 14, the other element 15 of which is mounted upon the end of a short shaft 16, carried in bearings 17' upon the frame of the machine. The element 15 has the seven open slots in its periphery for engagement with the single tooth of the element 14, whereby the continuous rotary motion of the shaft 4 is converted into intermittent rotary motion of the shaft 16 at the ratio of 7:1.

The spur gear 19 is rigidly mounted upon the shaft 16, immediately adjacent to the element 15, and engages the pinion 20, which latter is secured upon the end of the shaft 21, the gear ratio being 2:1. The shaft 21 is mounted in bearings 22 upon the frame 1, and carries at its opposite end the disk chuck plate 23. The chuck plate has mounted upon its face a series of seven chucks 24, of peculiar structure adapted to grip and hold the irregularly shaped raw stock from which the buttons are made.

The structure of the chucks will be more fully described hereafter.

At the right hand end of the frame 1 is the short cross shaft 25, having upon its end the miter gear 26 for engagement with the miter gear 27 upon the end of the shaft 11.

Upon the shaft 25, there are a number of cams 28, 29, 30, 31, 32, 33 and 34. The functions will be later described in detail. (See Fig. 17.)

The frame 1 is provided with the two hoods A and B, which serve as supports and bearings for various parts of the operative mechanism. These hoods are so located upon the frame that the chuck plate 23 may swing between their adjacent ends, and since the button stock must be operated upon simultaneously from opposite sides, parts of the operative mechanism respectively carried by the two hoods A and B are in many cases duplicates.

Upon the rear side of the frame, and carried in the bearings 35, 36 and 37, 38 in the end walls of the hoods A and B, are the two tubular tool actuating bars 39 and 40, arranged in axial alignment. Within these bars is the connecting rod 41, extending from the outer end of the bar 40 to a point within the bar 39, where it connects with the powerful contractile spring 42, the opposite end of which is secured to the outer end of the bar 39 by the cross pin 43. Adjusting nuts are provided upon the screw threaded end of the rod 41, to bear upon the outer end of the bar 40, so that the tension of the spring 42 may be regulated and the bars 39 and 40 may be drawn towards each other with greater or less force as desired or as necessity requires.

Upon the bar 39, the sleeve 44 is rigidly secured, said sleeve being connected to the bell-crank lever 45 by the link 46. (See Fig. 41.) The free end of the lever 45 is provided with a roller 45' which bears in the cam slot 47 of the cam disk 31, the latter being mounted upon the cross shaft 25, as above set forth. A similar sleeve 49 is mounted upon the bar 40 and connected by the link 50 to the bell crank lever 51, which latter has the roller 52 running in the cam slot 53 of the cam disk 32, the latter being also mounted on the cross shaft 25. The two bell crank levers are pivotally mounted upon the frame 1 at 48. The disks 31 and 32 are so placed upon the shaft 25 that their respective cam slots 47 and 53 will cause oscillations of the levers 45 and 51 in opposite directions at substantially the same time, so that the adjacent ends of the bars 39 and 40 will approach and recede from each other. (See Figs. 6, 41 and 42.)

Upon the outer ends of the bars 39 and 40 are the two-armed brackets 55, the arms 56, 57 of which serve as headstocks for the two tool spindles 58 and 59, which are provided with the sleeves 60, 61 (see Fig. 37) to slide horizontally in the arms 56, 57. Yokes 62, 63 integral with said sleeves, project laterally therefrom respectively for adjustment purposes as hereafter described. The sleeves 60, 61 are internally threaded to receive the

screw threaded spindles 58, 59, which are each provided with the hand wheels 64, 65, by which the spindles may be adjusted longitudinally within said sleeves. The inner ends of the spindles 58, 59 are provided with ordinary end couplings 66, 67, to receive the headed ends of the tool shafts 68, 69, which are mounted in bearings 70, 71 and 72, 73 in the end walls of the supporting hood A. Upon the shafts 68, 69 are the pulleys 74, 75, respectively, over which the drive belt 76 runs from any source of power, as from the pulley 77 on the shaft 78. The roughing and finishing cutting tools 79, 80 are set in the ends of the shafts 68, 69, and rotate therewith.

From the above description, it will be seen that as the points of the tools wear down and the tools become shorter, they may be longitudinally adjusted to provide for such wear by the hand adjustment of the spindles within the sleeves 60, 61, so that the two sets of tools upon the opposite side of the button stock may be made to approach each other to the same point at each stroke. The operative mechanism and adjusting mechanism for the cutting tools mounted upon the hood B are alike in all respects those just described as mounted upon the hood A; a detailed description of them is therefore deemed unnecessary.

The seven chucks 24, as shown in Figs. 30 to 33 mounted upon the chuck plate 23, are all identical in construction and uniformly spaced apart. A description of one will suffice. In an aperture 81, in the plate 23, the tubular jaw 82 is rigidly secured. The outer end of the jaw is serrated to form teeth which engage and firmly hold the button stock 83 in place. The chuck base 84 is secured to the plate 23 by the bolts 85 which pass through said plate and are screwed into bosses 86 in said base. Upon the outer face of the inner end of said base 84, is the projection 87, slotted as at 88, 89, to receive the two pivoted jaws or grippers 90, 91, the free ends of which are outwardly curved and register with the tubular jaw 82, so as to grip and hold the button stock in place during the several operations thereon. The jaws 90, 91 are guided in the slotted projection 92, and their outward movement is limited by the T-shaped head 93, which is held in place upon the projection 92 by the screw bolt 94. The plate 23 has the aperture 95 passing through a boss 95' upon its rear face, and located so as to come between the two jaws 90, 91. In the aperture 95 is the bolt 96, which extends between the jaws 90, 91, and is provided with the cross pin 97, by which it is connected to said jaws. The opposite end of the bolt 96 has the cross pin 98 and washer 99, between which and the boss 95' is the powerful spring 100, the

construction being such that said spring serves to draw the two jaws 90, 91 towards the jaw 82, and firmly grip the button stock in place.

While the cutting operation is going on, it is essential that there shall be no slipping or displacement of the button stock, nor any shifting of the chuck plate 23. In order to insure these two results, I employ two separate devices, whose description follows:—The chuck plate 23 is provided with the seven holes 101, as shown in Fig. 46 near its periphery and adjacent to the seven chucks 24, respectively. Upon the bracket 102, I mount the sliding bolt 103, in position to enter these holes successively as the plate 23 stops in its intermittent rotation at the point when the button stock is in correct position to be operated upon by the cutting tools. The reciprocation of the bolt 103 is effected by means of a lever 104, pivoted at 105 upon the frame 1. The lower end of this lever is connected by the rod 106 to the lower end of the cam lever 107, which is pivoted upon the arm 108, extending from the frame 1, above the cross shaft 25; the cam roller 109 upon the lower part of the lever 107 is in engagement with the cam 28 upon the shaft 25. The cam 28 is so placed upon the shaft 25 as to properly time the operation of the bolt 103 to correspond with the periods of rest of the plate 23, and to withdraw said bolt from the holes just prior to the time when the plate 23 begins to rotate. This setting of the bolt is effected by the contractile spring 110, one end of which is connected with the rod 106, and the other with the frame 1. This serves to shoot the bolt home into the holes 101 and hold it in place while the roller 109 is travelling upon the low part of the cam 28, the high part of which, through the intermediate connection described serves to withdraw the bolt 103 from locking engagement with the plate 23. In this manner the plate 23 is held from shifting or back-lash during the cutting operation. The other device has to do with the chuck jaws 90, 91, of the two particular chucks which for the time being, hold the button stock which is being operated upon by the cutting tools; during this time the tools exert a powerful twisting or turning force upon the button stock and it is liable to shift in the chuck unless some additional gripping force is brought to bear upon it. Upon the hood B, and in the long bearing 111, is the reciprocating rod 112, carrying at its inner end a presser foot 113, the face of which is arc-shaped and concentric to the apertures 95 in the chuck plate 23 as shown in Fig. 35; it is in position to bear upon the projecting ends of the two bolts 96 which are for the time being in front of it, and while the cut-

ting operation is going on. During the time that the plate 23 is rotating, the foot 113 is withdrawn from engagement with the bolts 96, so as not to interfere with the free rotation of the plate 23. The movements of the rod 112 and foot 113 are effected by the cam lever 114 see Figs. 5 and 43, which is pivoted at 115 upon the arm 116 projecting from the hood B. The lever 114 extends downwardly and is provided with a cam roller 117 near its lower end for engagement with the cam 30, upon the shaft 25. A powerful contractile spring 118 connects the free end of the lever 114 with the frame 1, and serves to give a strong but yielding pressure to the foot 113 upon the bolts 96, which is added to the pressure afforded by the springs 100, to more firmly grip the button stock between the chuck jaws 82 and 90, 91. The high part of the cam 30 serves to withdraw the foot 113 from the bolts 96. The two devices last described constitute important features of my invention, inasmuch as they insure perfect mechanical work upon the buttons which the machine is designed to turn out.

In the manufacture of buttons from the corozzo, or vegetable ivory nut, it is found that only the portions of the nut near the surface are the best for the purpose. The nuts are cut up into slabs as illustrated in Figs. 47, 48 of suitable size from which to cut one or more buttons. These slabs are of irregular shape and of varying thicknesses; a slab may be thick on one edge and thin upon the other as in Fig. 48. Unless some means are employed to regulate the cutters it would very often happen that they would not cut the button from the stock in such a place as to produce a perfect button, in other words, with a wedge shaped slab as shown in Fig. 48 the cutter at the rear would cut to such a depth that the front cutter would not touch the lower or thin spot thus leaving an imperfect or "bark" surface upon one side of the button. In order to overcome this defect, and thus save a large percentage of what would otherwise be useless button stock I have provided what I call a "stock spotter" which is in effect a set of selector mechanism which permits the machine to select automatically not only the best part of the stock in a regularly shaped slab but also to so adjust the cutters that they select a proper depth of cut to ensure a perfect button from an irregularly or wedge shaped slab.

The mechanism by which this is accomplished, consists of several groups of devices, which are successively actuated and so timed as to the other movements of the machine as to be entirely automatic, and depend upon the shape of the slab itself for their several adjustments.

Upon the back of the chuck plate 23 (see Figs. 30 to 33), and between the chucks, there is a series of seven recesses 119 with parallel side walls 120; these recesses extend to the open slots 121 in the peripheral flange 122 of the plate 23. Fitted to slide between the walls 120 as guides, are the seven cam plates 123, the outer ends of which are provided with cams 124 which may project through the slots 121 beyond the peripheral surface of the flange 122, the plates 123 are provided with slots 125 which take over the pins 126 in the plate 23 to limit the inward movement of the plates 123, which is effected by the springs 127 connecting the inner end of the plates 123 with the plate 23 near its hub. The outward movement of the plates 123 is effected by means of the bell crank lever 128, pivoted upon the bracket 129 upon the front face of the plate 23. One arm of the lever 128 projects through an aperture in plate 23 and into a slot 123' in plate 123. The other arm of the lever 128 extends toward the center of the plate 23. From this it will be seen that the oscillation of the bell crank lever 128 will reciprocate the plate 123 and cause the cam end 124 to project more or less from the periphery of the plate 23, while when free the plate 123 will be withdrawn by the spring 127. In a recess 130 extending laterally from one wall of the recesses 119, is a spring dog 131, pivoted at 132 with its free end bearing upon the edge of the plate 123. This free end is curved slightly eccentric to the pivot 132 and is roughened or serrated to grip the edge of the plate and prevent its recession under the tension of the spring 127. The structure is such that a movement of the bell crank lever 128 will move the plate 123 but the dog 131 will catch and hold said plate at whatever point it may be projected while the tripping of the dog 131 will release the plate 123 and permit the spring 127 to withdraw the plate into its recess. The oscillation of the lever 128 is effected by means of the selective mechanism and the parts related therewith. Upon the upper part of the hood A, as shown in Figs. 5, 6, 44 and 45, I mount a bearing bracket 132', in which the shank 133 of the "spotter" reciprocates and intermittently rotates with the axis of said shank in alignment with the center of the fixed jaws 82 as they are successively brought to rest during the intermittent rotation of the plate 23. The end of the shank is provided with an extended point 134. The shank 133 is connected to the oscillating lever 135 by the fork 136 the arms of which straddle the end 125 of the shank between the fixed collars 137 thereon; the lever 135 is pivoted at 138 upon the hood A, and its lower end is connected by the link 140 to the upper end of the cam lever 141, the latter being pivoted at 142, 130

and having at its lower end a cam roller 143, which bears upon the cam 29, upon the shaft 25. The heavy spring 144 connects the lower end of the lever 141 to the machine frame. The cam 29 has three cam points 29', about ninety degrees apart, and an arc shaped segment 29'' of about ninety degrees. A complete revolution of the shaft will give the shank 133 three thrusts toward the chuck 24 which at that moment is in alignment with, and then be withdrawn because of the roller 143 riding upon the segment 29''.

The shank 133 is intermittently rotated by means of a ratchet and gear mechanism mounted in the case 144'. (See Figs. 5, 6 and 27.) Upon the shank 133 is a pinion 145. In the ends of the case 144' is a small rock shaft 146, which carries the loose gear 147 to which the 8-toothed ratchet 148 is rigidly secured, said gear 147 meshing with the pinion 145. Upon the shaft 146, the disk 149 is rigidly secured, and upon the face of the disk the pawl 150 is pivoted for engagement with the ratchet 148. The end of the rock shaft 146 is provided with a crank 151, to which the thrust rod 152 is pivotally connected. The rod 152 extends forwardly and downwardly with its lower end passing through a guide 153, in position to ride over the cam teeth in the cam 154 upon the shaft 11. A strong spring 155 is connected to the rod 152 and to the hood B, the tendency of which is to pull the rod 152 downwardly and forcibly into contact with the cam 154. It will be noted that this cam has a circular segment of about 180 degrees and two ratchet-shaped cam teeth dividing the remainder of its periphery. The rotation of the shaft 11 and cam 154 will therefore cause the rod 152 to be thrust upwardly three times during each complete revolution; after the third thrust there will be a dwell or stop until the end of the rod 152 snaps over the end of the cam segment of cam 154. The cams 154 and 29 are so placed upon the shafts 11 and 25 respectively, that their segmental arcs will begin to actuate the shank 133 at the same time, the one to intermittently rotate and the other to reciprocate said shank. However there will be but three quarters of a complete rotation to four reciprocations of the shank, since it is unnecessary to change the position of the point 134 for the fourth "spot" upon one piece of the button stock and that for the first "spot" for the next succeeding piece of stock. Directly underneath the shank 133 and connected to it to reciprocate therewith by the arm or crosshead 155', is the pushrod 156, with its forward end provided with a feeler finger 157, in alignment and for engagement with the bell crank lever 128, upon the chuck plate 23.

If an irregularly shaped piece of button

stock is placed in one of the chucks 24, when it comes into alignment with the spotter point 134, the latter will be reciprocated four times, each time with the point striking the face of the button stock at a different point, and hunting for the thinnest "spot". The thinner the button stock is at one of these points or spots, the longer will be the stroke of the shank 133, and with it the push rod 156. But at each reciprocation of the push rod the finger 157 will engage, or at least be in position to engage the bell crank lever 128, and cause it to force the cam plate 123 outwardly beyond the periphery of the chuck plate 23, to an extent depending upon the stroke of the push rod 156 and shank 133, and that is governed by the thickness of the button stock. A thick "spot" will shorten and a thin "spot" will lengthen the stroke of the shank 133; so that the cam plate 123 will be thrust beyond the periphery of the chuck plate 23 to a distance corresponding to the thinnest "spot" in a piece of the button stock.

The cutters 79 are respectively the front and rear roughing cutters, and the cutters 80 are the finishing cutters; the roughing cutters and the finishing cutters operate simultaneously upon adjacent pieces of button stock; and since the said pieces of stock may be of different thicknesses, requiring a deeper cut on the bark side for one than for the other, it follows that the cutters must be separately adjusted for depth of cut, in order that the best part of the material be selected. However, the cam plate 123, having been adjusted for one piece of stock, serves to adjust the depth of cut for both cutters as and when that piece of stock is presented for its particular cutting operation, whether it be for the roughing cut or for the finishing cut.

The means used in conjunction with the spotting mechanism just described for accomplishing this adjustment consists of pairs of aligned shafts 158, 159, 158', 159', as shown in Figs. 5, 6 and 49 which extend through bearings 160, 161, 160', 161' in the bracket arms 56, and 57, of the bars 39 and 40 and through bearings in the end walls of the hoods A and B. Since these pairs of shafts are duplicates, a description of a single pair will suffice, it being understood that such description will apply to the other pair. Upon the outer ends of the shafts 158, 159 are the helical cams 162, 163, the cam slots of which receive the cam rollers 166 upon the arms of the yokes 62, 63, herefore referred to. The two shafts 158, 159, as above described are in alignment, and their inner ends telescope into the sleeve 167, to which they are both splined, so that both shafts will rotate together, while they both have the longitudinal movement of the bars 39, 40. The sleeve 167 is shouldered against

the end walls of the hoods A and B, so that it has no endwise movement. Surrounding the sleeve 167, is the torsion spring 168, one end of which is connected to the rigid collar 167' upon said sleeve, and the other end is firmly connected to the hood A. This spring is under heavy tension, and is of sufficient strength to rotate the shafts 158, 159 and with them, the cams 162, 163, 10 against the resistance offered by the rollers 166. Upon the sleeve 167 is the lateral arm 167'', in position to engage and rest upon the outer edge of the cam plates 123, as they are brought to rest adjacent thereto 15 during the intermittent rotation of the chuck plate 23. While I have called the elements 123 cam plates, yet they are more in the nature of stops, and the extent of their projection beyond the periphery of the 20 chuck plate 23 will therefore determine the final cutting of the cutters 79, 80, with respect to the button stock. For as hitherto described, a thin spot in the stock will necessitate a cut closer to the chuck jaw 82, 25 while a thick piece of stock will necessitate a cut farther away from said jaw, in order to cut a perfect button.

From the fact that the gear ratios have been so selected that the chuck plate 29 makes $2/7$ of a revolution for each revolution of the shafts 11 and 25, it will be seen that every alternate chuck will be brought into position successively, thus making two complete revolutions of the chuck plate necessary in order that all of the successive operations upon a single button may be complete. This makes it necessary to withdraw the arm 167" from the path of alternate cam plates 123, and permit said arm to fall back into contact with the intervening cam plates; otherwise a malfunction would follow. Upon the hub 169, of the bearing 35, the loose sleeve 170 is mounted to freely rotate. Upon this sleeve is a lateral crank arm 171, from which the link 172 leads to the cam lever 173, which latter is pivoted at 48 upon the frame of the machine. The lever 173 has a cam roller 174, which bears upon the cam 34 upon the extreme end of the cross shaft 25. The sleeve 170 has a projection 176 upon its upper side, in position to engage a rigid projecting finger 177 upon the shaft 158. The cams 31, 32, which operate the bars 39, 40, through the bell crank levers 45, 51, and the cam 34, are so related and timed that when the bar 39 and shaft 158 are withdrawn into their outermost positions, the cam 34 will through the connecting link 172, rock the sleeve 170, causing the projection 176 to engage the finger 177 and rock the shaft 158, thereby carrying the arm 167" from the path of the cam plate 123 which at that moment is swinging past it. However, the shaft 25 revolves continuously and as the roller 174 rides upon the low part

of the cam 34, the sleeve 170 is returned to its initial position, thereby permitting the spring 168 to rotate the shaft 158 until such time as the arm 167" comes into contact with the succeeding cam plate 123 which in the meantime advanced to its position and there stopped. The cam plate 123, having been previously adjusted by the spotting mechanism as described, it therefore follows that it is properly set to permit a button to be cut from the stock at the particular point determined by the spotting point. The sleeve 170

The other cutters are governed by substantially duplicate mechanism in all respects, with the single exception that in place of the arm 167", I provide a rock shaft 180 with an arm 181, and connect said arm with arm 182 upon the sleeve 183, by the link 184. This mechanism is solely for the purpose of shifting the arm 181 to the position for engaging the particular cam plate 123 which for the time being is governing the roughing cutter 79. The arm 181 is moved out of the path of alternate cams 123 in substantially the same manner as shown in connection with the arm 167" so that there is never any improper rotation of the sleeve 183. (See Fig. 35.)

The mechanism thus far described serves to cut the buttons by two separate operations, viz: the roughing cut, which shapes or forms the button in the stock; and the finishing cut, which completes the forming operation and smoothes the surface of the same to its final finish, the button being still connected to the body of the stock by a marginal fin as shown at *a*, Fig. 48. This fin is cut at the 7th step in the rotation of the chuck plate 23, by the severing cutter 185, which is carried by a reciprocating spindle 186, Figs. 1, 5 and 19 mounted on the frame 1, and driven by the belt 187 from any source of power. This spindle is reciprocated by means of a bell crank lever 188, pivoted at 189, which is oscillated by a lever 190, pivoted at 191, and having a cam roller 192 bearing upon the cam 193, upon the shaft 11. The spring 194 connects the lever 188 to the bearing 195 which is mounted upon the frame 1, and said spring serves to pull the spindle with its cutter against the fin *a*, and thus sever the otherwise formed button from the body of the stock. The spindle 186 is pushed in the opposite direction by the lever 188, lever 190, and cam 193, as will be readily understood.

When the button is severed from the stock or slab, the clutch which holds the stock in place upon the clutch plate 23, must be released and the stock discharged to make way for a new piece of button stock. This is done by means of the sliding rod 196, mounted in the bearing 197, Figs. 1, 19 and 24, in the standard 198, which is secured to the frame 1. The rod 196 is in direct alignment 130

with the bolts 96, when they arrive successively at the 7th step in the rotation of the chuck plate 23. The outer end of the rod 196 has the lever 199 connected to it, said lever being pivoted to the frame 1 at 200, and having the cam roller 201 at its lower end for engagement with the face of the cam disk 202, upon the shaft 11. The oscillation of the lever 199 by the cam 202 will 10 drive the rod 196 against the bolt 96 and thus raise the jaws 90, 91 from the surface of the button stock and thus release it from the chuck.

It sometimes happens that the button stock is gripped between the chuck jaws so tightly that it sticks, and will not drop out when the jaws are released, as described. In order to give it a sharp rap, and so break it loose, I provide a cam lever 203 (Figs. 1, 20 5 and 10), pivoted at 204 upon the frame 1, and extending up in alignment with the 7th step position. The lower end of the lever is bent into L-shape to engage a shouldered cam 205, upon the shaft 11. The spring 206 25 connects the upper arm of the lever 203 with the frame 1, and when the L-shaped end of said lever snaps over the shoulder of the cam 205, the upper end of said lever will fly forward and give the button stock a sharp 30 rap, thereby loosening it from the chuck jaw teeth.

Upon the return of the sliding rod 196 from engagement with the bolts 96, the spring 100 will again set the chuck jaws 90, 91 against the jaw 82. In order to open the said jaws for the insertion of a fresh piece of the button stock, I provide the sliding rod 207 Fig. 24 in alignment with the bolts 96, as they arrive at the 1st step 35 in the rotation of the chuck plate 23. The rod 207 is mounted in the upper part of the standard 198, and has its outer end connected with the upper arm of the bell crank lever 208, which latter is pivoted upon the standard at 209. The horizontal arm of 40 said bell crank lever is connected by the link 210 with the vertically sliding rod 211, which is mounted in bearings upon the frame 1. Upon this rod 211 are the two 45 cam rollers 212, 213, in position for engagement with the two cams 214, 215, upon the shaft 11, so arranged that upon the rotation of said cams, the rod 211 is reciprocated and its movement is communicated 50 to the rod 207 which is forced against the bolt 96, which at that time is in alignment with it. The depression of the bolt 96 will open the jaws 90, 91, and permit the insertion of a fresh piece of the button stock. 55 It will be noted that the cams 214, 215 are so placed upon the shaft 11, that for a portion of the revolution of the shaft 11, they are inactive so far as operating the rod 211, and that the rod 211 may be reciprocated 60 independently. This condition is utilized for the purpose of permitting the jaws 90, 91 to be manipulated so as to reopen them should the operator in his haste, improperly locate the button stock between the chuck jaws. The rod 211 is extended 65 downwardly some distance, and provided with a stop nut 216 at its lower end. Above this nut is a sliding sleeve 217, having a pair of lateral pins 218, for engagement with the bifurcated arms of the lever 219, mounted upon the horizontal shaft 220, which shaft is carried in bearings 221, 222 in the frame 1. The foot lever 223, pivoted upon one of the legs of the machine, is connected to a lateral arm 224, upon the shaft 220, by the link 225; by depressing said foot lever, the shaft 211 is rocked, and by the mechanism just described, the chuck jaws 90, 91 may be independently opened but only at such time as the two cams 214, 215 are in positions substantially 180 degrees from those shown in Figs. 24, 25 and 26.

It will be remembered that the cam plates 123 were set by the spotting mechanism as they successively pass the 2nd step or position of the chuck plate. They must be released, preparatory to being reset before they again reach their second step. Auxiliary mechanism operated by the chuck opening device just described is utilized for this purpose. In the standard 198, just above the rod 207, is another sliding rod 226, which is rigidly connected to the rod 207 by the cross head connection 227, so that both rods move together. The rod 226 has its inner end chamfered to form a cam 228, for engagement with the dog 181, which, as described holds the cam plate in its extended position, such engagement serving to trip said dog, and release the cam plate 123, 100 to permit the spring 127 to withdraw the cam plate 123 within the periphery of the chuck plate 23. Upon the advance of the chuck plate 23, to bring the released cam plate 123 to the next step or second position, the spotting mechanism will become operative to reset the cutters 79, and 80, as hitherto described.

In the operation of an automatic button machine, such as the one here described, it is often necessary to stop the machine at some stage of the operation in order to prevent mal-functioning, or for some other reason. But to bring the mechanism to a stop at the wrong stage of the operation may result disastrously to some part of the machine. Again, in the placing of the button stock between the chuck jaws, it may happen that the operator may not get it properly placed, and the time is so short that he may not have time to shift it into proper position before the jaws close. To permit the machine to run ahead at such a point

would result in spoiling the stock for that particular button, and it is desirable to stop the machine, open the jaws and set the stock in its correct position. In order to provide mechanism for these conditions, the following structure has been designed. The main driving shaft 4 is made tubular for a portion of its length, as shown in Fig. 28. The pulley 8 Figs. 3, 6, 7, 9 and 38 is mounted loosely upon the shaft, and provided with clutch member 230 upon its hub. Within this clutch member, and sliding upon the shaft 4, is the male clutch member 231, which is secured to the sliding push rod 232, with in the tubular shaft 4, by the pin 233. The opposite end of the rod 232 is connected by the pin 234 to the sliding collar 235, upon the shaft 4. Between the collar 235 and the bearing 3, is a strong spring 236, the tendency of which is to force the collar 235 along the shaft 4, and with it force the clutch member 231 into firm engagement with the member 230, so that the pulley 8 and shaft 4 will rotate together. Upon the shaft 4, and adjacent to the collar 235 is a sleeve 237, loosely mounted to slide upon said shaft, and bear upon the collar 235. Pivoted upon the bracket 2 at 238 is a lever 239, having its upper end bifurcated and straddling said sleeve, with the forked ends in position to bear upon the lateral projections 240 upon the sleeve 237. The lower end of the lever 239 extends downwardly and to the right (see Fig. 7), and is provided with an adjusting point screw 241 near its lower end. The bracket 2 has a projecting arm 242 which extends outwardly and laterally to the right and to the left as at 243 and 244, and has the bearings 245 for the end of the shaft 11, and other bearings for the stub rock shaft 246, which is mounted in the arm 244. Upon the inner end of the rock shaft 246 is the arm 247, in position to engage the point of the screw 241, upon the outer end of the rock shaft 246 is the arm 248, which extends to the right and above the end of the shaft 11, and carries at its free end a rocking cam lever 249. The lower end of this lever has the cam roller 250 in position to ride upon the periphery of the cam 251 on the end of shaft 11. The cam 251 has a single high point 252 upon it. The upper end of the lever 249 has a slot and pin connection with the link 253, the opposite end of which is pivotally connected with the arm 254 upon the shaft 220, which is rocked by the foot lever 223. The lower end of the cam lever 249 is connected by the spring 255 with the rigid arm 242, so that its normal tendency is to stand in the position shown in Fig. 7. This is the position it will take when the foot lever 223 is depressed; but with the foot lever raised, the link 253 will draw the lever 249 downwardly, thereby permitting the arm 248 also to be de-

pressed and correspondingly raising the arm 247, so that the lever 239 is free.

The spring 236 will now set the clutch mechanism above described, and the machine will proceed to do its work. If, however, the operator fails to properly locate a piece of button stock in the chuck, it becomes necessary to stop the machine; the foot lever 223 is depressed thereby rocking the shaft 220 and releasing the cam lever 249, so that the spring 255 will draw said cam lever into the position indicated in Fig. 7; when the cam point 252 rotates around and engages the cam roller 250, it will result in elevating the arm 248 and depressing the arm 247 against the lever 239, and cause the forked upper end thereof to engage the projections 240 of the sleeve 237, and depress said sleeve against the tension of the spring 236. It will be noted from reference to Fig. 38, that when the sleeve 235 is compressed against the spring 236, it will result in releasing the clutch member 231 from the clutch member 230. This will result in arresting the entire machine since with all of its cams and levers a considerable resistance is offered. The stopping of the machine, however, must be properly timed to take place when the chuck plate 23 is at rest; this is accomplished by taking advantage of the location of the two cams 214 and 215, on the shaft 11, which are utilized for opening the chuck jaws, as above described. When the two cams are in the positions indicated in Figs. 24, 25 and 26, it will be noted that the rod 211 cannot be moved vertically, but that when the shaft 11 rotates through an angle of about 90 degrees from the position indicated in said figures, the cam rollers 212 and 213 will be free. Under these conditions the chuck spring 100 will depress the bolt 96 against the rod 207, and therefore throw the bell crank lever 208 into the dotted line position indicated in Fig. 24. This will be the position assumed when the chuck jaws 90—91 grip a piece of button stock after the same is inserted therebetween. If the operator has not properly inserted the button stock at this point he may depress the foot lever freely, since under these circumstances the rod 211 will be somewhat elevated, and until the shaft 11 has rotated about 180 degrees from the positions indicated in Figs. 25 and 26, it can be operated by the foot lever; upon the depression of the foot lever 115 it will be seen that the sliding sleeve 217 with its lateral pins 218, will be drawn down by the bifurcated arms of the lever 219. This accomplishes two results, first the drawing down of the rod 211 through the mechanism 120 above described, will push the rod 207 against the bolt 96, which is adjacent thereto, and thereby open the chuck jaws. At the same time the rocking of the shaft 220 by the depression of the foot lever 223, will release 125 130

the cam lever 249, and thereby release the clutch members mounted upon the main shaft 4, as above described.

In the operation of the device, and from the gear ratios adopted, it will be noted that the chuck plate 23 advances 2/7ths of a revolution for each complete revolution of the shaft 11. Referring to Fig. 32 it will be noted that I have indicated the seven steps by the numbers I, II, III, IV, V, VI, and VII. The position, or step No. I, is the point at which the button stock is inserted into the chuck jaws. The position, or step No. II is the spotting position,—that is the position in which the spotting mechanism becomes operative to set the cam plates 123, in order to properly cut the button from the button stock held in the chuck, which is governed by that particular cam plate 123. Position No. III is the next advance, at which point the roughing cutter does its work. Positions IV and V are idle positions. Position No. VI corresponds to the finishing cut position when the finishing cutters advance upon the button stock in its finished form, but still leave it adhering to the button stock by the fin *a*, heretofore referred to. Position No. VII is the last position occupied by a piece of the button stock; in this position the severing cutter becomes effective, after which the chuck opening mechanism becomes effective to open the chuck jaws 90—91 and release the button stock, and also if such button stock should stick for any reason, as above described, the cam lever 203 snapping over the shoulder cam 205, gives the button stock a sharp rap and releases it.

The chuck plate 23 advances from step No. VII to step No. I, when, of course, it will receive a fresh piece of button stock as before described. It must be understood that as each of the chucks in the chuck plate advances to position I, they are made ready to receive a fresh piece of button stock, and that each of such chucks passes through the same cycle of operation above described; that the setting of the spotting mechanism at the position or step No. II, will set the cam plate 123 so that said cam plate operates both the roughing and the finishing cutter without resetting.

It remains to describe several minor features which add in their own way to the completeness of the operation of the device and result in a more perfect product. Among these minor features may be mentioned the chuck plate brake 260 shown in Figs. 19 and 23; said brake is mounted upon the end of a rock-shaft 261, which is supported in the bearing 262, upon the forward part of the standard 198 in such position that the brake 260 may bear upon the chuck plate 23. The shaft 261 is provided with an eccentric bearing 263, upon which the brake

260 is mounted. The opposite end of the shaft 261 has rigidly secured upon it the rock-arm 264, extending forwardly and downwardly and having on its under side a powerful flat spring 265, with the lower end thereof bent over to form a bearing contact with the cam 266 upon the shaft 11.

When the shaft 11 is rotated in the direction of the arrow, as illustrated in Fig. 23, the lower end of the spring 265 will ride upon the high point of the cam 266 and thus rock the shaft 261 in such a manner as to cause the brake 260 to bear upon the periphery of the chuck plate 23, and thus bring said chuck plate to a stop. The cam 266 is so located upon the shaft 11 that it becomes effective to operate the brake 260 only at the time when the single tooth member 14 is just leaving one of the slots in the member 15, for it is only when the single tooth of the member 14 is in engagement with one of the slots of the member 15, that the motion of the shaft 16 is communicated through the gears 19 and 20 to the chuck plate shaft 21; inasmuch as the chuck plate 23 is quite heavy it is desirable to reduce the strain which the momentum of its forward motion might have upon other parts of the mechanism; for this reason it is desirable, as above indicated, to provide the chuck plate brake 260 with the mechanism described, for operating the same.

Another minor feature is comprised in the guides for the two reciprocating bars 39 and 40. Referring to Fig. 6, it will be noted that the sleeves 44—49 are provided respectively with the downwardly extending arms 267 and 268, the lower ends of which are upwardly turned as at 269, and provided with friction rollers 270, which travel in the channels 271 upon the lower edge of the frame 1, as clearly illustrated in Fig. 39; thus any tendency of the two bars 39 and 40 to twist becomes effectively restrained by the two guide arms 267 and 268.

Another minor feature of importance is contained in the provision of means for carrying the shaft 25 past what might be termed "dead points," which are produced by the maximum strain due to the riding of the two cam rollers 45—52 over the high points in the two cams 31—32, and the consequent expansion of the spring 42, whose tendency is to draw the two bars 39 and 40 toward each other; this is accomplished by providing the shaft 25 with a cam 33, (see Figs. 6, 17 and 18), and a spring cam lever 272 pivotally mounted upon some part, as upon an adjacent leg thereof of the machine, and having a cam roller 273 to bear upon the periphery of the cam 33. A powerful spring 274, is connected to said cam lever 273, and to some part of the machine frame, as for example one of the legs thereof, as illustrated in Fig. 6; the tendency of

this cam lever is to serve as a sort of brake or resistance to the quick rotation of the shaft 25 due to the cam rollers 45—52, both entering the cam grooves 47—53, and running from their high points to their low points at the same time under the influence of the powerful spring 42; at such time the roller 273 will begin to ride upon the high segment of the cam 33, the result being that 10 between the two cam levers 45 and 51, and the cam lever 272, the shaft 25 is subjected to a comparatively uniform resistance throughout a complete revolution.

The button machine is entirely automatic 15 and requires only such attention as is necessary to properly locate the button stock between the chuck jaws in position I of the chuck plate.

I regard the spotting mechanism described above in detail, as one of the important features of my invention as it enables me to save a large percentage of button stock and to cut perfect buttons therefrom, whereas hitherto because of the peculiar shapes of the slabs of button stock only culls or discards could be cut from them and yet the material itself is such that a perfect button can be cut from it if it is only cut from the proper part of such button stock.

I claim:

1. In a button making machine, the combination of a chuck for gripping and holding irregularly shaped button stock, a stock spotting finger for successively advancing against a plurality of points in the face of the button stock, a cutting tool and means for advancing said cutting tool against the button stock to a depth determined by the maximum advance of said spotting finger.

2. In a button making machine, the combination of a chuck for gripping and holding an irregularly shaped slab of button stock, a stock spotting finger with means for successively advancing said finger to contact at a plurality of points upon one face of said button stock, a pair of button cutting tools arranged in alignment with each other upon opposite sides of said button stock, and means for advancing said tools against said stock to cut a button therefrom, the degree of such tool advance being governed by the maximum advance of said spotting finger.

3. In a button making machine, the combination of a circular chuck plate, an odd number of button stock gripping chucks upon the face of said plate, means for intermittently rotating said plate to bring said chucks successively into cutting position, a stock spotting finger mounted adjacent to the path of said chucks, means for successively advancing said finger to contact with a plurality of points in the face of said button stock, a button cutting tool,

means for advancing said tool against said button stock, and operating connections between said finger and said tool for limiting the advance of said tool to a point determined by the maximum advance of said finger.

4. In a button making machine, the combination of a chuck plate, means for intermittently giving said plate a partial revolution, means for gripping a plurality of irregularly shaped slabs of button stock upon one face of said plate, a stock spotting finger mounted adjacent to the path of said button stock as the same is intermittently advanced by the rotation of said chuck plate, means for advancing said finger into successive points of contact with the button stock, a button cutting tool, means for advancing said cutting tool upon said button stock, as the same is brought to rest adjacent thereto, and cam operated connections between said tool and finger for limiting the advance of said tool to a point determined by the maximum advance of said finger.

5. In a button making machine, the combination of a chuck plate, a button stock gripping chuck thereon comprising a pair of pivoted jaws and a fixed jaw, a spring actuated bolt for drawing said jaws together to grip a work-piece therebetween, and a cam-actuated presser foot adapted to bear upon said bolt for increasing the pressure of said pivoted jaws upon said work-piece.

6. In a button making machine, the combination of a chuck plate, a plurality of button stock gripping chucks thereon, each comprising a fixed tubular jaw and a pair of pivoted jaws co-operating therewith for gripping a slab of button stock therebetween and a spring actuated bolt connected to said pivoted jaws, means for intermittently rotating said chuck plate to bring each of said chucks successively into operative position, and a cam-actuated presser foot adapted to bear upon the end of said bolt for increasing the gripping action of said pivoted jaws while said chuck is in operative position.

7. In a button making machine, the combination of a chuck plate having a series of seven button stock holding chucks arranged in a circle and uniformly spaced apart on the face thereof, means for rotating said plate two sevenths of a revolution at a time, to intermittently and successively advance said chucks into seven positions of rest during two complete revolutions of said plate, and means for giving a slab of button stock held in one of said chucks a roughing cut in its third position of rest, a finishing cut in its sixth position of rest and a button severing cut in its seventh position of rest.

8. In a button making machine, the combination of a circular chuck plate, a series

of seven button stock holding chucks uniformly spaced apart upon the face of said plate, means for intermittently rotating said plate two sevenths of a revolution at a time to advance the alternate chucks of said series successively into the same operative position of rest, and means for simultaneously and progressively operating upon the stock held in four of said chucks during the periods of rest.

9. In a button making machine, the combination of a chuck plate having a series of seven button stock holding chucks spaced apart in the face thereof, and means for intermittently rotating said chuck plate two sevenths of a revolution at a time, whereby each of said series of chucks is brought successively into the same operative position during two complete revolutions of said chuck plate.

10. In a button making machine, the combination of a circular chuck plate having a series of seven chucks spaced apart upon the face thereof, means for intermittently rotating said plate two sevenths of a revolution at a time to bring alternate chucks successively into the same operative position of rest, whereby each chuck will be brought into said position of rest during two complete revolutions of said chuck plate.

11. In a button making machine, the combination of a circular chuck plate, having a series of seven chucks spaced apart upon the face thereof, means for intermittently rotating said plate two sevenths of a revolution at a time to bring alternate chucks successively into the same operative position of rest, means for progressively operating upon work-pieces held in said chucks during each of said periods of rest.

12. In a button making machine, the combination of a circular chuck plate having a series of seven spring actuated chucks spaced apart upon the face thereof, means for intermittently rotating said plate two sevenths of a revolution at a time to bring alternate chucks successively into initial position of rest, and means for opening said chucks to receive work-pieces as and when said alternate chucks are so brought to said initial position of rest.

13. In a button making machine, the combination of a circular chuck plate having an odd number of work-piece gripping chucks spaced apart upon the face thereof, a continuously rotating shaft, means connecting said shaft with said chuck plate for converting the continuous rotation of the former into an intermittent rotation of the latter twice the spacing of the chucks to bring alternate chucks successively into an initial position of rest, a chuck opening device, and means actuated by said shaft for operating said chuck opening device to open said alternate chucks as and when said

chucks are brought successively to said initial position of rest.

14. In a button making machine, the combination of a circular chuck plate having an odd number of work holding chucks spaced apart on the face thereof, means for intermittently rotating said chuck plate two spaces at a time to bring alternate chucks successively into operative positions of rest, and means for automatically locking said chuck plate against rotation as and when said plate is so brought to rest.

15. In a button making machine, the combination of a circular chuck plate having an odd number of chucks spaced apart upon the face thereof, means for intermittently rotating said chuck plate two spaces at a time to bring alternate chucks successively into an operative position of rest during two complete revolutions of said plate, a button cutting tool and means for successively advancing said tool upon button stock held in said chucks as and when said chucks are successively brought to said operative positions of rest.

16. In a button making machine, the combination of a stock spotting device, comprising an intermittently rotating reciprocating shaft, an offset point adapted to engage at different spots an irregularly shaped work-piece held in alignment with said shaft and thereby limit its reciprocation, a push rod reciprocated by and to the same extent as said shaft, and an adjustable cam plate located in front of and actuated by said push rod to vary the adjustment thereof in accordance with the extent of reciprocation of said shaft.

17. In a button cutting machine, the combination of a pair of aligned tubular tool actuating bars, a spring within and connected to the nonadjacent ends of said bars for drawing the same toward each other, and cam actuated mechanism sliding said bars away from each other, a button cutting tool connected to and reciprocated by each of said bars respectively and adapted to operate upon opposite faces of a button blank simultaneously.

18. In a button cutting machine, the combination of a pair of aligned tubular tool actuating bars, a spring within and connected to the nonadjacent ends of said bars for drawing the same toward each other and cam actuated mechanism sliding said bars away from each other, a button cutting tool connected to and reciprocated by each of said bars respectively and adapted to operate upon opposite faces of a button blank simultaneously, and means for adjusting said tool longitudinally in the direction of its travel.

19. In a button cutting machine, the combination of a pair of aligned tubular tool actuating bars, a spring within and con-

nected to the nonadjacent ends of said bars for drawing the same toward each other and cam actuated mechanism sliding said bars away from each other, a button cutting 5 tool connected to and reciprocated by each of said bars respectively and adapted to operate upon opposite faces of a button blank simultaneously, and automatic means for successively presenting work-pieces in the 10 path of said tool to be cut thereby.

20. In a button making machine, the combination of a chuck plate having a plurality of button stock gripping chucks upon the face thereof, a radially slidable cam plate 15 arranged adjacent to each of said chucks, means located adjacent to the path of said chucks for gauging the thickness of the button stock held thereby and for correspondingly projecting said cam plates respectively, button cutting tools located adjacent to the path of said chucks, and means for reciprocating said tools against the button stock to cut buttons therefrom at points therein determined by the projection of said 25 cam plates from the periphery of said chuck plate.

21. In a button cutting machine, the combination of a circular chuck plate having a plurality of button stock gripping chucks 30 upon the face thereof, means for intermittently rotating said plate to bring alternate

chucks successively to initial position, means operative only during the rest periods of said chuck plate for opening said chucks to permit the insertion of button stock therein 35 and for automatically closing thereon before the rotation of said plate again begins, and manually operated means timed to be operative only during such rest periods for reopening said chucks to permit the readjustment of button stock which may have been 40 improperly placed.

22. In a button cutting machine, the combination of a circular chuck plate having a plurality of button stock gripping chucks 45 upon the face thereof, means for intermittently rotating said plate to bring alternate chucks successively to initial position, means operative only during the rest periods of said chuck plate for opening said chucks to 50 permit the insertion of button stock therein and for automatically closing thereon before the rotation of said plate again begins, manually operated means timed to be operative only during such rest periods for 55 reopening said chucks to permit the readjustment of button stock which may have been improperly placed, and emergency connections from said manually operated means for simultaneously stopping the intermittent 60 rotation of said chuck plate.

EMANUEL CLEMENS.
